UNITED STATES PATENT OFFICE.

WILSON NEAR, OF HUMBERSTONE, ONTARIO, CANADA.

WASHING-MACHINE.

SPECIFICATION forming part of Letters Patent No. 388,998, dated September 4, 1888.

Application filed July 7, 1887. Serial No. 243,618. (Model.)

To all whom it may concern:

Be it known that I, WILSON NEAR, a subject of the Queen of Great Britain, residing at Humberstone, in the Province of Ontario and 5 Dominion of Canada, have invented certain new and useful Improvements in Washing-Machines; and I do hereby declare that the following is a full, clear, and exact description of the invention, which will enable others to skilled in the art to which it appertains to make and use the same.

This invention relates to that class of washing-machines which embody a wash-board, and beaters mounted upon a crank-shaft in 15 such a manner that the clothes are rubbed between the wash-board and beaters.

The object of my invention is to provide a simple and improved washing-machine of this class which will possess advantages in point 20 of inexpensiveness, durability, ease of operation, and general efficiency, and in which the motion imparted to the beaters by the crank-shaft will impart to the clothes a constant rolling and progressive movement from one side 25 to the other of the tub.

A further object of my invention is to secure a constant pressure upon the clothes, whether there be few or many in the tub, whereby the action and cleansing effect of the 30 beaters upon the clothes will always be even and regular, this being effected by improved spring mechanism for regulating the operation of the beaters.

In the drawings, Figure 1 is a perspective 35 view of a washing-machine embodying my improvements. Fig. 2 is a vertical longitudinal sectional view. Fig. 3 is a vertical transverse section on the line $x-x$, Fig. 2. Fig. 4 is a corresponding view on the line $y-y$. Fig. 40 5 is a detail perspective view of one of the beaters, illustrating its means of attachment to the crank-shaft and its connection with the spring-regulating devices.

Corresponding parts in the figures are 45 noted by the same letters of reference.

Referring to the drawings, A designates the tub or body of the machine, which comprises vertical sides $a-a$, an inclined end, a' , a rear end, a'' , and a bottom, a^3 , the bottom being 50 preferably inclined upwardly toward said inclined end.

B designates a transverse strip or abutment located at the bottom of the inclined end a' and adapted to be engaged by the lower edge of a transverse wash-board, C, which is preferably provided with a corrugated face, c , and is retained down in position by inwardly-projecting plates D at the top of the sides $a-a$. These plates are secured to the sides of the tub, and to one end of said plates are pivoted 60 arms E, provided on their under edge with projections e , adapted to engage the top edge of the wash-board to retain the same against displacement and in the position to which it has been adjusted. By this arrangement it is 65 manifest that the wash-board may be readily adjusted at the desired inclination with relation to the beaters to suit different sizes and quantities of clothes to be cleansed, and owing to the fact that the wash board is not permanently connected to the tub it can be readily removed, when desired, to facilitate the removal of the clothes or cleansing of the tub.

F designates the transverse beater-shaft, which has bearings $f-f$ at the sides $a-a$, and 70 may be provided with a crank-arm, G, to enable its operation by hand-power, or it may be provided with a band-wheel or other device for communicating motion from a motor or other power. The crank-shaft is made up of 75 a series of cranks, f'' , arranged on different planes with relation to the length of the shaft and forming bearings for the beaters, the beaters being retained between shoulders f'' , formed by the portions connecting the cranks. 85

In practice I prefer to employ ten beaters, and from the arrangement shown and described it will be obvious that each beater is mounted eccentrically with relation to the plane of the bearings of the shaft, whereby its lower end 90 will be carried upwardly and rearwardly and downwardly and forwardly during the revolution of the shaft in the plane indicated by dotted lines, Fig. 2. The lower ends of the beaters which operate with relation to the wash-board are preferably provided with transverse ribs or corrugations f^3 , and during the rearward movement of the beater the pressure upon the clothes is relieved, thus allowing them to turn, by which arrangement and operation of a series of independent successively-operating and eccentrically-mounted beaters 95 100

a constant rolling and progressive movement of the clothes from one side to the other of the tub is effected.

The beaters are removable from the shaft 5 and interchangeable, this being permitted by a spring-plate, H, secured at the rear edge of the beater, and comprising a spring loop or hook, h, adapted to be sprung over the cranks of the shaft (see Fig. 5) and forming the bearing for the beater. The spring-plate may be formed of a continuous strip of metal bent double, as shown, and at its upper end the plate is bent outwardly and bifurcated to form two spring-arms, h' h', which retain and form 15 a bearing for a detachable T-head, I, secured to one end of a coiled spring, J, by staples j, or in any other suitable manner. A corresponding T-head, K, is similarly secured at the other end of the coiled spring of each 20 beater, and is adapted to be engaged with a notch, l, in the edge of a flange, L, secured at the end of the tub or body. This flange is provided with a longitudinal groove, l', forming a bearing for the T-head K, and the series 25 of notches or recesses l are provided in the grooved portion of the flange L. The office of these coiled springs is to cause the lower ends of the beaters at their forward stroke to exert a constant and even pressure upon the 30 clothes, whether there be few or many in the tub, thus securing an even and regular action which enhances the efficiency of the machine and obviates damage or unnecessary wear upon the clothes.

35 I claim as my invention—

1. The combination, in a washing-machine of the class described, of a tub or body, a wash-board mounted therein, a transverse crank-shaft embodying a series of cranks on different planes with relation to the length of the shaft, a transverse series of beaters eccentrically mounted with relation to the bearings of the shaft upon said cranks, and coiled springs connected with the upper ends of the beaters, 40 substantially as and for the purpose set forth.

2. The combination, in a washing-machine of the class described, of the tub or body, a transverse adjustable wash-board mounted therein, the transverse shaft provided with 45 the series of cranks f'', beaters mounted upon

said cranks eccentrically with relation to the bearings of the shaft, plates secured to the beaters and forming curved spring-arms, a flange projecting from the body and provided with a series of notches, and coiled springs 55 having T-heads at their ends respectively engaging said notches and the spring-arms upon the beater, substantially as and for the purpose set forth.

3. In a washing-machine, the combination 60 of the tub or body provided with a transverse strip or abutment at its bottom and inwardly-projecting plates at its top, a transverse wash-board retained in position by said ridge and plates, pivoted arms engaging the top of the 65 wash-board to retain it in adjusted position, a transverse shaft provided with a series of cranks, a series of beaters provided with spring-plates forming a detachable connection and bearing with the cranks and having curved 70 arms at their upper ends, a flange upon the body formed with a longitudinally-grooved portion provided with a series of notches, and coiled springs provided at their ends with T-heads respectively engaging said notches and 75 the curved arms upon the beaters, substantially as and for the purpose set forth.

4. In a washing-machine of the class described, the combination, with a shaft embodying a series of cranks and connecting portions 80 forming shoulders, of a series of removable and interchangeable beaters having a spring-plate secured at their rear edge and comprising a loop or hook adapted to be sprung over the cranks of the shaft and retained by said shoulders, substantially as and for the purpose set forth. 85

5. In combination with the series of detachable beaters provided with the plates having a spring loop or hook forming the bearing and 90 provided with a bifurcated upper end forming spring-arms, the coiled springs provided with a T-head engaging said arms, substantially as and for the purpose set forth.

In testimony whereof I affix my signature in 95 presence of two witnesses.

WILSON NEAR.
